UNITED STATES PATENT OFFICE

GIUSEPPE POCOROBA, OF NEWARK, NEW JERSEY

MEANS FOR IDENTIFYING BULLETS

Application filed January 24, 1930. Serial No. 422,974.

My present invention relates generally to bullets, and has particular reference to a method and means for making bullets identifiable.

5 It is a general object of my invention to provide a bullet of the character used in rifles, revolvers, and the like, which is so constructed that the slug thereof may be positively identified at all times, even after it 55
 10 has been fired from the bullet. The identification which I seek to accomplish is with respect to the origin of the bullet, and by my invention it is possible to trace the source 60
 15 of a bullet not only to a particular manufacturer or dealer, but also to identify the same as having been manufactured or sold at a particular time. The identification means 65
 20 which I provide serves to render every individual bullet distinctive and distinguishable from any other individual bullet.

Briefly, my invention resides in associating with the slug of the bullet an identification element which is of such a character as to travel with the slug even when the same 70
 25 is fired from a gun, and to remain with the slug even after it has been lodged in the object shot at. The identification element which 75
 30 I employ may broadly be said to be embedded in the slug. In one form of my invention, for example, the element is a strip of metal or the like which is completely invisible from the outside of the bullet and which is embedded in its entirety within the slug, as by 80
 35 associating it in a suitable manner with the mold in which the slug is cast.

In modified forms of my invention, the identification element which is embedded in the slug is so constructed and of such a nature as to have a portion thereof exposed on the 85
 40 exterior of the slug.

Regardless of the particular shape of the identification element or of the particular manner in which the same is embedded in the slug, it is a feature of my invention always to provide the element of a material 90
 45 which is of higher melting point than that of the slug itself, which is capable of receiving and retaining identification indicia, and 95
 50 which is preferably in the form of a metallic strip or the like.

Whether the element is embedded in its entirety or with a part exposed, its configuration and its method of association with the slug are such that removal thereof is totally impossible without mutilating the entire slug 55 and rendering it useless thereafter. Accordingly, any bullet constructed in accordance with my present invention and which is actually fired from a gun may at any time thereafter be traced to a particular time and source 60 of origin by an examination of the slug itself.

For the attainment of the foregoing objects and such other objects as may herein-after appear or be pointed out, I have constructed a device embodying the features of 65 my invention and illustrated in the accompanying drawing, in which—

Figure 1 is a side view of a typical bullet constructed in accordance with my present invention; 70

Figure 2 is a plan view of one form of identification element;

Figure 3 is a plan view of the element of Figure 2 shown in unrolled condition;

Figure 4 is a side view of a slug with a 75 portion broken away to illustrate a modified form of the invention;

Figure 5 is a cross-sectional view taken substantially on the line 5—5 of Figure 4;

Figure 6 is a fragmentary cross-section 80 similar to the upper portion of Figure 4, showing a further modification;

Figure 7 is a view similar to Figure 3, showing a different manner of providing 85 identification indicia;

Figure 8 is a view similar to Figure 7, showing a further method of applying 90 identification;

Figure 9 is a fragmentary longitudinal sectional view of the rear end of a slug, showing a further modification; and

Figure 10 is a view of the slug of Figure 9, taken from the right.

In Figure 1, I have shown a typical bullet, 95 which consists of the shell 15 and the slug 16. In the form shown in this figure, an identification element 17 is completely embedded within the slug 16. This element is more fully illustrated in Figures 2 and 3 and 100 consists of an elongated strip of material,

preferably metal, upon which, or into which, identification indicia have been inscribed.

In Figure 3, for example, I have shown one method of identifying the strip 17. I have shown three letters 18 which may, for example, represent respectively a particular manufacturer and a serial number. In other words, the letter A may represent a particular manufacturer of the bullet. The combination of letters C. R. may represent a serial number (of which 676 variations are possible by this particular method), and the numerals 19 may represent a particular bullet of that particular serial number. I also prefer to construct the strip 17 of a colored material, the color variations enabling me still further to broaden the number of possible distinctions, and serving perhaps as an indication of the year of manufacture.

The strip of Figure 3 is comparatively small, and in the form illustrated, it is rolled up into a spiral, as shown in Figure 2, and is then embedded in the slug 16 during the molding or casting of the latter. At any subsequent time, whether the slug has been fired or not, a removal of the strip 17 and an examination of the markings thereon will serve to identify the particular bullet, and may in that way assist in the identification 30 of the user thereof.

In Figures 4 and 5 I have illustrated a modification wherein a strip 20 is made of elastic material, such as spring metal, whereby the tendency of the strip to unroll during the molding or casting of the slug will cause it to assume an embedded position somewhat like that illustrated in Figure 5. It is obvious that a portion 21 of the identification strip will be exposed on the surface 40 of the slug 22. The exposed surface of the strip 20 will lie flush with the exposed surface of the slug 22; will not interfere with the contemplated use of the bullet; will indicate to the user of the bullet that it is identifiable and may, in this way, deter the user from using it for an illegitimate purpose.

In any event, it is to be noted that the strip 20 is entirely irremovable from the slug 22 without a mutilation of the latter sufficient 50 to render it unusable.

In Figure 6, I have shown a slight modification wherein the cross-sectional configuration of a similar strip 23 is trapezoidal, the outer surface 24 being of less width than the inner surface 25, and thereby rendering it still more difficult to remove from the slug. The construction of Figure 6 dovetails the strip 23 within the body of the slug 26, and thereby 60 enhances the security with which the strip is held in permanent association with the slug.

In Figures 9 and 10, I have illustrated a still further modification wherein the identification element is in the form of a countersunk disc having a central, substantially circular portion 27 and a marginal portion 28.

Connecting the portion 28 with the portion 27 is the conical portion 29 which is constructed to converge rearwardly. In this form of the invention, the element is embedded in the rear face of the slug 30, and it is obvious that its removal, without mutilation of the slug, will be extremely difficult, if at all possible. Furthermore, the construction of Figures 9 and 10 is such as to leave the markings on the element unaffected by a discharge of the slug 75 from the bullet shell.

In the form shown in Figures 9 and 10, the identification indicia may be of a more general character, as shown in Figure 10, this being possible because of the larger size of 80 element which this embodiment permits.

It is, of course, obvious that the particular manner of marking the identification element is relatively immaterial. I have illustratively shown one convenient method of 85 accomplishing this in Figure 3. In Figures 7 and 8 I have shown a further method which may be desirable under certain circumstances. In Figure 7, the strip 31 is provided with two punch marks 32 and 33. The particular location of these punch marks with respect to one or more predetermined cross-sectional patterns will serve to identify the strip. The cross-sectional patterns are indicated in Figure 7 and show the possibility of providing identification marks of tremendous variety by 90 this simple method.

In Figure 8, I have shown a further development of the idea of Figure 7, the strip 34 being provided not only with two punch marks 35 and 36, but also with the two notches 37 and 38. Here, too, the relative positions of the notches and of the punch marks with respect to a predetermined pattern (roughly indicated in Figure 8) will serve to identify the strip and distinguish it from thousands 95 of others.

It will also be understood that the particular material of which the slug is made has no effect upon my invention, because the identification element will in every event be made of a material having a higher melting point. For example, if the slug is made of lead, as is usually the case, the identification element may be of iron or steel. Steel is particularly desirable for the further reason that it is easily engraved or marked and will retain such marks for indefinite periods of time.

The various modifications shown in the drawing are merely illustrative of the variations possible by those skilled in the art. Therefore, it will be understood that I do not intend to limit myself to any particular configuration of identification element nor any particular manner of associating the same with the slug. Furthermore, the methods by which identification elements of this character may be distinctively marked are numerous and may be varied to suit differing requirements.

It will thus be seen that my invention is extremely simple and of great value. Bullets are usually sold in packages of fifty. If every bullet has its own identification mark, and if it is made compulsory that dealers keep records of the particular bullets sold to particular persons, any illegitimate use of a bullet can be traced with great facility to the original purchaser thereof.

10 In the drawings, I have illustrated my invention in an implement to which I have referred to as a bullet. It will be understood that my invention is applicable to any explosive instrumentality of this character in which an explosive charge is employed to throw a projectile such as a slug of a bullet or shot from a cannon or shot-gun.

15 Having thus described my invention and illustrated its use, what I claim as new and desire to secure by Letters Patent is—

20 1. In a bullet, a slug having embedded therein an element bearing identification indicia; said element comprising an elongated metallic strip rolled into a spiral.

25 2. In a bullet, a slug having embedded therein an element bearing identification indicia; said element comprising an elongated metallic strip of spring metal having a portion exposed on the exterior surface of

30 the slug.

3. In a bullet, a slug having embedded therein an element bearing identification indicia; said element comprising a substantially C-shaped strip of spring metal, the

35 ends of the C extending in convergence toward the interior of the slug.

4. In a bullet, a slug having embedded therein an element bearing identification indicia; said element comprising a substantially C-shaped strip of spring metal, the

40 ends of the C extending in convergence toward the interior of the slug; said strip having a trapezoidal cross-section.

45 5. In a bullet, a slug having embedded therein an element bearing identification indicia; said element comprising a rolled metallic strip of trapezoidal cross-section, said strip being substantially concentric with

50 the axis of the slug and having the surface of lesser width outward.

6. An identification element of the character described, comprising a strip of metal with notches in its edges, said notches being relatively positioned in accordance with a predetermined cross-sectional pattern, whereby said element may be identified by the number and relative arrangement of said notches.

60 7. The combination of a relatively soft slug of a bullet and a folded, relatively long and narrow strip therein, said strip having thereon means to identify the maker of the bullet and being made of material of such toughness as to permit the removal of the

strip from the slug, after distortion of the latter by impact, without destruction of the identifying means.

8. The combination of a relatively soft slug of a bullet and a strip therein, said strip having thereon means to identify the bullet and being made of material of such toughness as to permit the removal of the strip from the slug, after distortion of the same by impact, without destruction of the identifying means.

9. The combination of a relatively soft slug of a bullet and an insert therein, said insert having thereon means to identify the bullet and being made of material of such toughness as to permit the removal of the insert from the slug, after distortion of the same by impact, without destruction of the identifying means.

10 In witness whereof I have signed and sealed this specification this 22nd day of January, 1930.
